PORTABLE DATA SET

Robert P. Mulholland, Centerville, Ohio, assignor to
Monarch Marking Systems, Inc., Dayton, Ohio

Filed Oct. 22, 1970, Ser. No. 25,606

Term of patent 14 years

Int. Cl. D14—02

U.S. Cl. D26—5

FIG-1

FIG-2

FIG. 1 is a perspective view of the top, front, and left side of a portable data set showing my new design;

FIG. 2 is a bottom plan view of the portable data set shown in FIG. 1;

FIG. 3 is a left side elevational view;

FIG. 4 is a right side elevational view;

FIG. 5 is a rear elevational view; and

FIG. 6 is a front elevational view thereof.

I claim:

The ornamental design for a portable data set, substantially as shown.
